SUBSTATION TELEPHONE SET

Harry H. Ide, La Grange, Ill., assignor to Associated Electric Laboratories, Inc., Chicago, Ill., a corporation of Delaware

Application February 15, 1932, Serial No. 592,987

4 Claims. (Cl. 179—100)

This invention relates in general to telephone substation sets, but more particularly to telephone substation sets for use in small intercommunicating systems, and the principal object of 5 the invention is to design a substation telephone that is economical to manufacture, durable in construction, simple to operate, and at the same time retains all of the features common to a regular telephone substation, such as talking, 10 listening, and signalling.

An object of the invention resides in the design of a new and improved circuit arrangement for a substation telephone set in combination with another similar telephone to form a private inter- 15 communicating system.

In accordance with the above object only a single pair of line wires, together with a battery conductor are provided between two permanently connected telephones. Signalling and talking 20 takes place over the battery conductor and one of the line wires when one telephone calls the the other; and when the second telephone calls the first, signalling takes place over the battery conductor and the other line wire while talking 25 proceeds over the first line wire and the battery conductor.

A particular feature of the invention resides in providing a three-position switch operating member which in one position with the handset resting 30 on the telephone cradle, closes a point in the ringing circuit of that telephone and with the handset removed closes a point in its talking circuit; while with the handset removed, the member may be manually actuated by the user 35 to signal the other telephone station, thereby dispensing with the use of a separate ringing or signalling key.

Other objects and features not specifically pointed out will be apparent hereinafter in the 40 description, which, together with the accompanying two sheets of drawings, illustrates a preferred embodiment of the invention. In the drawings, Fig. 1 illustrates a perspective front view and on a reduced scale of a cradle type of 45 telephone constructed in accordance with the invention; Fig. 2 is a full size top view of the base of the telephone of Fig. 1 illustrating the apparatus mounted thereon; Fig. 3 shows a full size side view of the switch operating member 50 detached from the telephone together with the contact springs actuated thereby, all in their normal position with the handset resting on the member; Fig. 4 is a similar view with the handset removed from the switch actuating member and 55 the contact springs shown in the talking posi-

tion; while Fig. 5 illustrates the position of the contact springs and the actuating member when the user is signalling the other telephone; Fig. 6 illustrates an underside view of the handle of the handset with the transmitter and receiver units 60 removed to show the construction of the same; Fig. 7 shows a side view of the receiver unit with the casing in section; Fig. 8 is a side view of the transmitter unit with the casing and the microphone unit shown in section; Fig. 9 is a perspective view of the microphone unit, together with its support; Fig. 10 is a bottom view of the dummy calling device of Fig. 1 showing the ratchet mechanism for generating sound waves simulating dialling; and Fig. 11 is a schematic diagram of 70 the circuit connections extending between two telephones.

Referring now specifically to Fig. 1, the base 5 of the telephone is formed out of a sheet metal stamping. A U-shaped cradle member 6 is riveted to the top of this base and has a pair of ears for supporting the handset 7. A reinforcing member 8 is welded between the two ears of the cradle member 6 and has projections extending through the top of the base 5 for securing it 75 thereto. A switch operating member 9, made of insulating material, extends through the reinforcing member 8 and a hole in the top of the base 5. This member projects upward a sufficient distance so as to be operated by the handset 7 when it is in the normal position, as shown in Fig. 1. The handset 7 has a transmitter unit 10 and a receiver unit 11 secured on opposite ends of it by means of pairs of screws 12.

Referring to Fig. 2, the base plate 14 is made 80 of stamped metal of a size sufficient so as to form a perfect fit with the inside of the base member 5. The upturned rim 15 fits inside of the base 85 of the telephone 5 and is properly located by means of an appropriate notch 17 engaging a similar one in the base 5. The plate 14 is also provided with projecting portions 16 to slightly raise the major portion thereof off any supporting surface upon which it may be set. A clip 18 is riveted to the plate 14 and serves as a support 90 and strain reliever for the telephone wires entering the rear of the base 5 through a hole (not shown). A pair of insulating plates 19, one supported on top of the other, are riveted to the base plate 14 and serve as a mounting plate for the 95 wire terminals 20, 21, and 22 to which the conductors entering the telephone stand are connected. A sheet of insulating material 23 is riveted to the base plate 14, and supports a metal 100 plate 24 riveted onto it. The metal plate 24 has 105 110

a pair of upwardly projecting portions, one of which supports the buzzer coil 25, while from the other the armature 26 and interrupter arrangement are supported. A bracket 30 is riveted to 5 the base plate 14 and serves as a support for a plurality of contact springs 32, 33, 34, 35, and 36 by means of which the necessary circuit switching operations are performed. Each of these contact springs is separated by a suitable 10 insulating plate and the assembly as a whole is clamped to the bracket 30 by means of a pair of screws 31. The bracket 30 supports the set of contact springs in a position immediately below the switch operating member 9 so that they can 15 be actuated thereby. An insulating bushing 37 is secured to spring 33 and is adapted under certain conditions to close springs 35 and 36.

Fig. 3 illustrates in side elevation the position of the switching member 9 with the handle of the 20 handset 7 normally resting upon it between the ears of the cradle member 6 of the telephone. In this position the contact springs 32 and 33 are separated, while contact springs 33 and 34 are made, and as will be further pointed out hereinafter, prepare the circuit of the buzzer of the 25 telephone for operation. Contact springs 35 and 36 for signalling the other telephone are at this time not closed.

Fig. 4 shows the set of springs in the position 30 in which they are operated when the handset 7 has been removed from the cradle 6 thereby allowing the switching member 9 to move upward to permit the contact springs 32 and 33 to close the circuit of the handset 7 so that talking and listening can take place, and at the same 35 time to open the contact springs 33 and 34 to interrupt the circuit of the buzzer of the telephone. Springs 35 and 36 are not closed in this position of the switch member 9. Fig. 5 shows 40 the position of the switch actuating member 9 when the user of the telephone holds it actuated to signal the person at the other telephone. This is accomplished by the user pressing down the switch operating member 9 until his finger engages 45 the base of the cradle portion 8, which, it will be noted, is a little further than illustrated in Fig. 3 in which the handset 7 rests upon the switching member 9. In the position shown in Fig. 5 the switch member 9 opens the 50 contact springs 32 and 33, closes contact springs 33 and 34, and by means of the insulating bushing 37 actuates the contact springs 35 and 36 to close the signalling circuit to the buzzer of the other telephone. Figs. 3, 4, and 5, as pointed out, 55 illustrate the three different positions assumed by the switch operating member 9 during the operation of the telephone.

In Fig. 6 is shown a full size view of the handset. It is constructed of relatively thin sheet 60 metal which is first blanked out and then stamped and the edges bent over towards each other so that the handle portion 7 assumes a circular cross section having the slots 40 and 41 at right-angles to each other where the ends come together. 65 This arrangement does not require any overlapping or riveting of the ends. Shallow cup-shaped members 43 and 44 are formed on each end of the handle 7, the receiver unit fitting in the cup-member 44 while the transmitter unit 70 fits in the cup-member 43. These units are each secured in the cup-members by means of a pair of screws 12 extending through holes 45 and temporary threaded holes in the bottom of the casings of the receiver and transmitter units. 75 An opening 42 in the bottom of the cup member

43 serves as an entrance for the conducting wires of the units. The wires between the receiver unit in the cup member 44 and the transmitter unit in the cup member 43 extend through the hollow handle 7 of the handset and are inserted by being forced through the slot 40 of the handle 7.

The receiver unit shown in Fig. 7, comprises 80 essentially the stamped metal casing 11 which is cup-shaped, together with the ear piece 50 which is crimped around the flared edges of the cup 11 as indicated at 51. The diaphragm 52 of the receiver is clamped between the crimped edges of the ear piece 50 and the casing 11. This arrangement precludes the possibility of opening up the receiver unit by unskilled persons or children 85 and prevents damage to the internal mechanism. The receiver coil 53 has a threaded extension 54 formed on the end of its core so that the adjusting nut 55 can be threaded onto it. A flat leaf spring 56 normally urges the coil 53 towards the diaphragm 52 and the air gap between the end of the core and the diaphragm is conveniently 90 adjusted by turning the nut 55 on the extension of the core 54 to compress or expand leaf spring 56. A lock washer between the nut 55 and the casing 11 and another between the spring 56 and the end of the core 53 securely hold the coil 100 in the desired adjusted position.

The transmitter unit shown in Fig. 8 comprises a stamped metal casing 10, similar to the 105 casing 11 of the receiver. The mouthpiece 60 has a flared edge which is crimped to the top flared edge of the casing 10. A microphone supporting member has a pair of oppositely disposed legs 62 and 63 on each side of the microphone 110 which are clamped between the mouthpiece 60 and the top of the casing 10 forms the sole support of the microphone unit. The microphone supporting bracket has an enlarged central portion with an opening therein into which the insulating cup-shaped microphone container 64 extends. A short projecting ear 68 extending from either side of the supporting bracket is clamped over the back side of the cup-member 64 and securely holds the microphone unit in position 115 120 opposite the sound openings in the mouthpiece 60. The microphone unit comprises a button-shaped rear electrode 65 having a stem projecting from the rear of the insulated cup 64 so that a wire can be soldered to it. The front electrode 125 comprises preferably a thin gold plated diaphragm 66 spaced opposite the rear electrode 65 by the felt washer 69 and held in position in the insulated cup 64 by the metal ring 67. The intervening space between the front electrode 66 and 130 rear electrode 65 is occupied by a suitable amount of granulated carbon resistance material. Fig. 9 clearly illustrates the general configuration of the microphone cell together with its supporting bracket. Sound waves projected through the 135 mouthpiece 60 and upon the gold plated electrode 66 will compress and expand the carbon granulated material in the microphone cell and vary the resistance of the electrical circuit extending from the front electrode 66 to the rear 140 electrode 65 in the ordinary operation of the transmitter.

While this telephone as described and constructed meets all the requirements of a practiced 145 telephone for intercommunicating use, it will be appreciated that, because of the low construction cost it finds a ready market as a toy. A telephone, to be put to such a use, must be ruggedly constructed due to the rough handling which 150 ordinarily prevails when an instrument of this

nature is used as a toy. The construction of the transmitter and receiver units, which are sealed in their casings, readily meets these requirements. In order that an instrument of this nature may have a further appeal to juveniles, an arrangement simulating the calling device of an automatic telephone is provided. This comprises a disc 13 having a number of holes, as shown in Fig. 1, with suitable numerals visible therethrough. The disc 13 is arranged for rotation on a rivet 73 extending through the base member 5. On the rear end of this rivet a ratchet arrangement 70 is attached, as shown in Fig. 10. The ratchet 70 has a pair of pawls 71 and 72 cut on opposite sides thereof arranged so that by rotation of the dial 13 these pawls will rotate over the teeth 74 of the ratchet wheel and generate a sound or noise similar to that made by an ordinary calling device.

Fig. 11 schematically illustrates the circuit connections existing between a pair of telephone instruments A and B each constructed according to the invention. A single pair of line conductors 75 and 76 extend between the telephones A and B, conductor 75 being tied to terminals 21-21', and conductor 76 being tied to terminals 22-22' of the respective substations. A small source of current which may be supplied by dry cells C is provided and one post of the battery extends to terminal 20 while the opposite post extends to terminal 20'.

In the normal position the handsets 7 and 7' of the substations A and B, respectively, are resting on their associated switch operating members 9 and 9' and maintain the sets of contact springs in the position illustrated in Fig. 3. With both telephones in this position when the user at the substation A desires to call the person at substation B the handset 7 is removed from the cradle 6, thereby permitting the switch actuating member 9 to rise and allow contact springs 32 and 33 to close and springs 33 and 34 to open as shown in Fig. 4. A circuit is thereby completed from one pole of battery C, to terminal 20, contact springs 33 and 32 of substation A, in series with the receiver coil 11 and transmitter 10 of the handset 7, line conductor 76, terminal post 22' of substation B, normally-closed contact springs 33' and 34', interrupter contacts 26', the winding of the buzzer 25', terminal post 20' and to the other post of battery C. The buzzer 25', terminal post 20' and to the other post of battery C. The buzzer 25' of substation B, however, does not operate in this circuit because of the relatively high resistance of the receiver 11 and transmitter 10 of the headset 7 in substation A. To signal the person at substation B, the user of the telephone at substation A now presses down the switch operating arm 9 into the position in which it is shown in Fig. 5. This action separates contact springs 32 and 33, brings together springs 33 and 34 and likewise brings together contact springs 35 and 36. This last pair of springs close a shunt circuit around the receiver 11 and transmitter 10 of the handset 7 at substation A to remove the resistance of these elements from the signalling circuit so that this circuit is now completed from one pole of battery C, terminal post 20, through closed contact springs 36 and 35, terminal 22, conductor 76, closed contact springs 33' and 34' of substation B, interrupter contacts 26', the buzzer winding 25', terminal 20' to the other pole of battery C. The buzzer 25' rapidly opens and closes its circuit at the interrupter contacts 26' to signal the called subscriber. The user of the telephone at substation A after a short interval releases his finger from the switch member 9, thereby permitting the contact springs of his telephone to assume the talking position shown in Fig. 4 and awaits the response of the person at substation B.

The user of the telephone at substation B in responding to the calling signal removes the handset 7' from the switch actuating member 9', thereby permitting contact springs 32' and 33' to close. Contacts 33' and 34' at the same time are opened and disconnect the buzzer 25' from the battery circuit. A talking circuit between the two telephones is now established over the following path; one pole of battery C, terminal 20, closed contact springs 33 and 32, receiver 11 and transmitter 10 of the handset 7 in series, terminal 22, conductor 76, terminal 22', contact springs 33' and 32', transmitter 10' and receiver 11' in series in the handset 7', terminal 20' and then to the other pole of battery C. Current for talking and listening is furnished by the battery C. Upon the replacement of the handsets at substations A and B the circuits are again placed in their original condition.

The circuit connections of telephone B with the line wires is slightly different from telephone A and the operation of this substation will now be pointed out. Upon initiating a call the user of the telephone at substation B removes his handset 7' from the switch operating member 9', thereby permitting contact springs 32' and 33' to close, and at the same time contact springs 33' and 34' to open. A circuit path is thereby prepared extending from one pole of the battery C, to terminal 20', receiver 11', transmitter 10' of the handset 7', contact springs 32' and 33', terminal post 22', conductor 76. However, due to the fact that at this time contact springs 35 and 36 of substation A, as well as, contacts 32 and 33 are open, no current flows over this circuit. In order to signal the party at the substation A the user of the telephone B presses down the switch operating member 9' with his finger, as shown in Fig. 5, and closes the contact springs 35' and 36'. Contacts 32' and 33' are also opened at this time and, therefore, no current flow takes place through the units of the handset 7'. The signalling circuit extends from one pole of battery B, terminal 20', interrupter contact 26, winding of the buzzer 25, contact springs 34 and 33, terminal 20 to the other pole of battery B. The buzzer 25 consequently operates to signal the user of the telephone at substation A. By listening in occasionally between intervals during his operation of the switch actuating member 9' the user at substation B ascertains when the person at substation A responds to the signalling by the removal of his handset 7' from the cradle of the telephone. When this occurs the circuit for the buzzer 25 is opened at contact springs 33 and 34 to stop the signalling if such signalling has not already been stopped, and at contacts 32 and 33, a circuit extending through the transmitter 10 and receiver 11 of the handset 7 at substation A is completed over terminals 20 and 22, in series with the transmitter 11' and receiver 10' of the handset 7' at the substation B, and conversation now may proceed. The replacement of the respective handsets upon the substation cradle members restore the circuits to their normal condition.

It should be noted particularly in the above circuit operations that when telephone station A signals station B the signalling current for

operating buzzer 25' takes a path extending over the leads extending from the battery C and the line conductor 76, while when station B signals station A the buzzer 25 is operated over a circuit 5 path extending from the battery conductor and line wire 75. In all cases talking and listening takes place over a circuit from the battery conductor and over the line wire 76, to the exclusion of the line conductor 75. From this it is seen 10 that the line wire 76 is used for both signalling and talking, while line wire 75 is used only for signalling. By arranging the circuits in this manner the number of conductors extending between the telephones is reduced as well as effecting 15 a simplification of the internal wiring of each telephone.

What is claimed is:

1. In a telephone set, a base having a cradle member thereon, a handset normally resting on 20 said cradle, a set of circuit controlling springs within said base, a handset controlled switching member extending exterior to said cradle member controlling certain of said springs responsive to the removal of said handset from the cradle 25 member for performing certain circuit switching operations, said switching member than manually operated to perform a switching operation of said springs different than those performed by said handset.
2. In a telephone set of the cradle type having 30 a handset, a switching member in said set engaged by said handset in its normal position, a plurality of sets of contact springs in said set controlled by said switching member, one set of said 35 contact springs closed by said switching member in its normal position with the handset on the set, another set of contact springs closed by the removal of said handset from the switching mem-

ber, and a third set of contact springs closed by said switching member only by direct manual actuation thereof.

3. In a cradle telephone set having a handset, a plurality of sets of contact springs, a switching member in said set for controlling said contact springs, said handset normally resting on said telephone in engagement with said switching member to close one set of contact springs and open a second set, said member operated to open 80 said first set of springs and close said second set consequent to the removal of the handset from the cradle and the release of said switching member, said switching member thereupon operative independent of any action of said handset to again close said first set of springs and open 85 said second set and in addition close a third set of said springs.

4. In a cradle type telephone having a handset, a set of five contact springs, a switching member 95 for actuating said springs, said member having one end thereof protruding from the cradle set a predetermined maximum distance under the tension of the second spring of said set, the first spring thereof at the same time engaging second 100 spring, the slight movement of said member resulting from the placing of the handset on the cradle disengaging said first and second springs and bringing said second springs into engagement with a third spring, said member also directly operated manually to a position in the direction of but beyond that attained by the placing of the handset on the cradle, and means in 105 said second spring actuating the fourth spring of said set into engagement with the fifth spring 110 consequently only to the manual movement of said member.
